DESIGN FOR A TRACTOR RADIATOR

Roy H. Allen, Plymouth, Ohio, assignor to The Fate-Root-Heath Company, Plymouth, Ohio, a corporation of Ohio

Application January 23, 1934, Serial No. 50,489

Term of patent 7 years

To all whom it may concern:

Be it known that I, Roy H. ALLEN, a citizen of the United States, residing at Plymouth, in the county of Huron and State of Ohio, have invented a new, original and ornamental Design for a Tractor Radiator, of which the following is a specification, reference being had to the accompanying drawing, forming a part thereof, in which

Figs. 1 and 2 are front and side elevations, respectively, and

Fig. 3 is a top plan view of a tractor radiator embodying the design.

The radiator illustrated which, embodies the design of the present invention, comprises a shell including top and bottom members, side members and an intermediate vertical member positioned forward of the side members. The top and bottom members have front surfaces directed diagonally forward toward the middle of the radiator. The two core members extend diagonally forward toward the middle of the radiator, each being arranged between the intermediate vertical member of the shell and one of the side members thereof.

I claim:

The ornamental design for a tractor radiator, substantially as shown and described.

ROY H. ALLEN.
